CLAIM

The ornamental design for a toothbrush kit, as shown and described.

DESCRIPTION

FIG. 1 is an exploded top, front, right perspective view of a toothbrush kit showing my new design;

FIG. 2 is a bottom, rear, left perspective view thereof;

FIG. 3 is an enlarged top, front, right perspective view of the rinsing cup, shown unfolded;

FIG. 4 is an enlarged bottom, rear, left perspective view of the rinsing cup, shown unfolded; and,

FIG. 5 is an enlarged perspective view of the toothbrush, shown folded.

All undisclosed or partially disclosed surfaces are plain and unornamental.

The rinsing cup and toothbrush are shown separately for clarity and ease of illustration.
